UNITED STATES PATENT OFFICE.

LOUIS L. DRIGGS, OF NEW YORK, N. Y.

SHELL-FUSE.

1,311,795.

Specification of Letters Patent.

Patented July 29, 1919.

Application filed January 2, 1917. Serial No. 140,181.

To all whom it may concern:

Be it known that I, LOUIS L. DRIGGS, a citizen of the United States, residing at New York, in the county of New York and State of New York, have invented certain new and useful Improvements in Shell-Fuses; and I do hereby declare the following to be a full, clear, and exact description of the invention, such as will enable others skilled in the art to which it appertains to make and use the same.

My present invention relates to improvements in shell fuses, and is intended to provide a percussion fuse which is especially adapted for use with projectiles adapted to strike a target at a comparatively low velocity, such as howitzer shell fired from long ranges and at a comparatively low initial velocity.

My invention relates to shell fuses of that character in which a plunger is held in place by a spring clip having weighted arms, which arms are thrown out of engagement by the centrifugal force due to the rotation of the shell by the rifling of the gun. When the velocity of the shell in flight decreases, the rotary motion of the shell also decreases until the centrifugal force becomes so low that the spring arms tend to swing back into engagement with the plunger; and my present invention is intended to provide a fuse having a heavy plunger with an automatic lock for the spring arms when they are once thrown out under the action of the centrifugal force, so that the said arms will positively and safely lock the plunger in the fuse, except when the shell is spun up, and after the shell has spun up the weighted arms are distended and are positively locked, thus leaving the plunger in the operative position during the remaining portion of the trajectory of the shell.

My invention will be understood by reference to the accompanying drawings, in which:

Figure 1 is a section through the fuse stock showing the plunger and the spring clip in elevation;

Fig. 2 is a front view of the plunger;

Fig. 3 shows a section through the plunger along the line 3-3 of Fig. 2;

Fig. 4 is a detail showing the spring clip in perspective; and

Fig. 5 is a plan view of the locking attachment for automatically locking the arms of the spring clip in the distended position.

1 represents the fuse stock of a base fuse having the closing plug 2, perforated as at 3, and carrying the primer 4.

Attached to the plug 2 is the spring clip 5, consisting of an annular central portion, and the two resilient arms 7, which terminate in weighted portions 8. The spring clip may be made of a single piece of metal stamped out and bent to the shape as shown, or the weights 8 may be attached to the resilient arms 7.

The plunger 10 consists of a body portion 11, provided with a firing point 12 in its center, with the reduced stem 13 and the flange 14; and the sides of the body portion of the plunger are cut away, as at 15, to permit the free springing in of the resilient arms 7, and also to permit the weights 8 to engage the stem 13 and to lock the plunger against sufficient longitudinal movement to strike the primer should the shell be accidentally dropped endwise, or fall in any other way, except after it has been fired from the gun.

Mounted in the bottom of the fuse is a ring 17, provided with inclined resilient catches 18, inclined upwardly and outwardly, as shown in Figs. 1 and 5, which catches will permit the weights to swing outward when the shell is spun up, but will lock the weights against subsequent movement inward after being once distended, as shown in dotted lines in Fig. 1.

These catches project into notches 14^a in the flange 14 when the plunger is in the safety position shown in Fig. 1.

As a result of this herein described construction the fuse is absolutely safe, no matter should the shell be accidentally dropped, or subjected to careless and rough handling; but when once the shell is set spinning the fuse is primed, and the plunger is ready for action, when the forward movement of the projectile is suddenly arrested as when it strikes the ground or the target.

While I have shown the invention as applied to a base fuse, it will be obvious that by a reversal of the parts it may be adapted to a fuse mounted in the nose of the shell.

Any suitable primer may be mounted in the fuse stock, and the nature of the priming charge may be varied at will.

It will be noted that the plunger is shown as comparatively heavy, so as to deliver an adequate blow to the primer.

The plunger is mounted to slide freely in the fuse stock so that it will not be necessary to have the shell strike end on for the fuse to operate. The spring clip being held absolutely clear of the plunger after the shell is spun up, it will be seen that even if the shell were to strike base forward, as occasionally happens, the rebound of the plunger would cause it to strike the primer and explode the shell.

It will be obvious that various modifications might be made in the herein described device, and in the construction, combination and arrangement of parts which could be used without departing from the spirit of my invention.

Having thus described my invention what I claim and desire to secure by Letters Patent of the United States is:—

1. In a percussion fuse for shells, the combination with a fuse stock and a primer carried thereby, of a plunger slidably mounted in said fuse stock and provided with a heavy body portion having parallel grooves in opposite sides thereof, a firing point carried by said body portion, and a flanged stem projecting rearwardly from said body portion, a spring clip having resilient arms adapted to pass freely in said grooves, and weights carried by said arms adapted to normally engage said flanged stem, but to fly clear thereof due to centrifugal force when the shell is spun up, and means for automatically holding said arms in the distended position after the shell is spun up,

said means comprising yielding spring catches adapted to be pressed back by said weights on their outward movement, but to lock the same against return movement inward as the centrifugal force decreases due to the slowing down of the rotary motion of the shell, substantially as described.

2. In a percussion fuse for shells, the combination with a fuse stock and a primer carried thereby, of a plunger slidably mounted in said fuse stock and provided with a heavy body portion having parallel grooves in opposite sides thereof, a firing point carried by said body portion, and a flanged stem projecting rearwardly from said body portion, a spring clip having resilient arms adapted to pass freely in said grooves, and weights carried by said arms adapted to normally engage said flanged stem, but to fly clear thereof due to centrifugal force when the shell is spun up, and means for automatically holding said arms in the distended position after the shell is spun up, said means comprising a locking ring having oppositely-disposed spring catches inclined upwardly and outwardly therefrom, said spring catches permitting the outward movement of said weights; but locking the same against return movement inward as the centrifugal force decreases due to the slowing down of the rotary motion of the shell, substantially as described.

In testimony whereof, I affix my signature.

LOUIS L. DRIGGS.
